UNITED STATES PATENT OFFICE.

HAROLD F. SHEPHERD, OF GROVE CITY, PENNSYLVANIA, ASSIGNOR TO THE BESSEMER GAS ENGINE COMPANY, OF GROVE CITY, PENNSYLVANIA, A CORPORATION OF PENNSYLVANIA.

HOT PLUG.

Application filed October 13, 1921. Serial No. 507,519.

To all whom it may concern:

Be it known that I, HAROLD F. SHEPHERD, a citizen of the United States, residing at Grove City, in the county of Mercer and State of Pennsylvania, have invented new and useful Improvements in Hot Plugs, of which the following is a specification.

The invention is especially designed for hot plugs for explosive engines and is particularly desirable where it is electrically heated. Hot plugs of this general type have been previously invented by me as indicated in Patent #1,317,900, Oct. 7th, 1919.

The invention is illustrated in the accompanying drawing which shows a vertical central section through the plug.

1 marks a mounting having a shoulder 2 which is adapted to fit into an opening leading to the explosive chamber of an explosive engine, the mounting being provided with perforations 3 through which the attaching bolts extend. A projection 4 extends from the mounting 1, and the receptacle 5, the walls of which form the hot plate, is on the end of the projection 4. This receptacle is preferably cylindrical and closed by a cap 6 having its joint sealed by welding 7. An electrical element 8 is preferably arranged in the receptacle 5 and one end of the conductor 9 of said element is grounded in the receptacle. The conductor with the usual element sheath is led out through an opening 10 in the projection 4, the passage 10 extending through the mounting. The conductor is insulated by the sheath from the walls of the opening 10 and extends through the insulating cap 11 and is connected to a terminal 13, the terminal being secured to the usual wire in the usual manner.

The receptacle is filled with mercury, or some similar substance, vaporizing at a temperature which is the desired ignition temperature of the wall forming the hot plate on the receptacle. The end of the conductor 9 contacts with its sheath as shown at the right of the figure and this sheath being immersed in the mercury grounds this end of the conductor through the mercury and the walls of the receptacle. A passage 16 is formed in the projection but off-set from the passage 10, the outer end of this passage being closed by a plug 17. An upwardly extending projection 18 is formed on the mounting 1 and has a passage 19 leading

from the passage 16 and forming a connection with a condensing chamber 20, the walls 21 of which are provided with a corrugated surface so as to increase the condensing surface. A screw-threaded end 22 is arranged at the bottom of the condensing chamber and this is screwed into the top of the projection 18 and the joint welded by welding at 23.

With this construction the hot plug may extend horizontally in the combustion chamber and the condensing chamber may be arranged vertically without the combustion chamber, thus making a very desirable and convenient arrangement. In starting the engine, the current is turned into the heating element, the mercury heated to an ignition temperature and the heat thus conveyed to the walls of the receptacle. After the engine is started and the hot plug is subjected to the explosion temperature the hot plate is maintained at this desired temperature by the constant vaporization of the mercury which carries the heat into the condensing chamber where it is dissipated through the walls of the condenser and the mercury as it is condensed is returned to the receptacle 15. In this way a constant temperature is maintained in the receptacle in the manner expressed in my former patent. After the engine starts the current is cut off.

What I claim as new is:—

1. In a hot plug, the combination of a receptacle, the walls of which form the hot plate of the plug; a mounting from which the receptacle projects; a condenser carried by the mounting, said condenser being out of alinement with the receptacle and arranged above the same; a connection between the condenser and the receptacle; and a liquid in the receptacle vaporizing at the desired predetermined temperature.

2. In a hot plug, the combination of a receptacle, the walls of which form the hot plate of the plug; a mounting from which the receptacle projects horizontally; a condenser carried by the mounting and extending vertically therefrom; a connection between the condenser and the receptacle; and a liquid in the receptacle vaporizing at the desired predetermined temperature.

3. In a hot plug, the combination of a receptacle, the walls of which form the hot plate of the plug; a mounting from which the receptacle projects; a condenser carried

by the mounting, said condenser being out of alinement with the receptacle and arranged above the same; a connection between the condenser and the receptacle; a liquid in the 6 receptacle vaporizing at the desired predetermined temperature; and a heating element arranged in the receptacle.

4. In a hot plug, the combination of a receptacle, the walls of which form the hot 10 plate of the plug; a mounting from which the receptacle projects; a condenser carried by the mounting, said condenser being out of alinement with the receptacle and arranged above the same; a connection between 15 the condenser and the receptacle; a liquid in the receptacle vaporizing at the desired predetermined temperature; a heating element arranged in the receptacle; and a conductor leading from the heating element 20 through the mounting, said conductor being off-set from the connection leading to the condenser.

5. In a hot plug, the combination of a receptacle, the walls of which form the hot 25 plate of the plug; a mounting from which the receptacle projects horizontally; a con-

denser carried by the mounting and extending vertically therefrom; a connection between the condenser and the receptacle; a liquid in the receptacle vaporizing at the desired predetermined temperature; a heating element in the receptacle; and a conductor leading through the mounting, said conductor being off-set from the connection between the condenser and the receptacle. 30 35

6. In an electrically heated hot plug, the combination of a receptacle, the walls of which form the hot plate of the plug, said receptacle being formed with an initial opening at its inner end and sealed with a 40 cap welded in said opening; a condenser arranged above and out of alinement with the receptacle; an electric element in the receptacle; a conductor leading to the element; and a mounting carrying the receptacle and the condenser, said mounting having a passage therethrough for the conductor and a passage leading from the receptacle to the condenser. 45

In testimony whereof I have hereunto set 50 my hand.

HAROLD F. SHEPHERD.
